Patented Oct. 5, 1915.

*Inventor
Harold D. Bowie.*

by his Atty. Benedict S. Wise

UNITED STATES PATENT OFFICE.

HAROLD D. BOWIE, OF MAHWAH, NEW JERSEY, ASSIGNOR TO E. I. HORSMAN CO., A CORPORATION OF NEW YORK.

DESIGN FOR A TOY.

47,908.

Specification for Design.

Patented Oct. 5, 1915.

Application filed July 8, 1915. Serial No. 38,758. Term of patent 3½ years.

To all whom it may concern:

Be it known that I, HAROLD D. BOWIE, a citizen of the United States, residing at Mahwah, county of Bergen, State of New Jersey, have invented a new, original, and ornamental Design for a Toy, of which the following is a specification, reference being had to the accompanying drawing, forming a part thereof, which is a perspective of a toy wagon and doll showing my new design.

I claim—

The ornamental design for a toy as shown.

In witness whereof, I have signed my name to this specification in the presence of two witnesses.

HAROLD D. BOWIE.

Witnesses:

H. R. SQUIER,
JACOB LASKER.
